UNITED STATES PATENT OFFICE.

JOHN J. MACKAY, OF LAKE CHARLES, LOUISIANA.

NUT-LOCK.

1,239,414.

Specification of Letters Patent.

Patented Sept. 4, 1917.

Application filed December 22, 1916. Serial No. 138,422.

To all whom it may concern:

Be it known that I, JOHN J. MACKAY, a citizen of the United States, residing at Lake Charles, in the parish of Calcasieu and State of Louisiana, have invented certain new and useful Improvements in Nut-Locks, of which the following is a specification, reference being had therein to the accompanying drawing.

10 This invention relates to a nut lock and has for its principal object the production of a nut which is provided with a transverse opening adapted to receive the key which will tangentially engage the threaded portion of the bolt thereby preventing the unscrewing of the nut.

Another object of this invention is in the production of a key which is provided with bifurcated end portions.

20 Still a further object of this invention is in the production of a bifurcated portion upon one end of a key which bifurcated portion is provided with a beveled outer face so as to lie flush with the corresponding face 25 of the nut.

With these and other objects in view, this invention consists of certain novel constructions, combinations and arrangements of parts as will be hereinafter more fully described and claimed.

In the drawings:

Figure 1 is a side elevation of a bolt and nut showing the device in operation.

Fig. 2 is a section taken on the line 2—2 35 of Fig. 1.

Fig. 3 is a section taken on the line 3—3 of Fig. 2.

Fig. 4 is a detail perspective view of the key used in connection with this device.

40 Fig. 5 is a section taken on the line 5—5 of Fig. 2.

By referring to the accompanying drawings by numerals, it will be seen that 1 designates the bolt which is provided with the 45 threaded portion 2 which is adapted to receive the nut 3. The nut 3 is provided with the transverse opening 4 which extends wholly within the body of the nut as is clearly shown in Fig. 2.

50 By referring to Fig. 3, it will be seen that this opening is adapted to receive the key 5 in such a manner that the threaded portion 2 will bite into said key so as to prevent the nut from unscrewing on the 55 threaded portion.

By referring to Fig. 4, it will be seen that

the key used in connection with this device is provided with the bifurcated end portions 6 and 7. The end portion 7 is bifurcated so as to form the slot 8 and the end 6 is bifurcated so as to form the slot 9. It will be seen by referring to the same figure that the end portion 6 is beveled so that the same will fit flush with the face 8 of the nut 3 as is clearly shown in Fig. 2 and it will also be seen that this end is provided with the channel portions 10 within the slot 9. The purpose of these channels 10 is that when the key is inserted in the portions shown in Fig. 2 a nail or other like implement may be driven into the channel 10 in such a manner as to spread the slot sufficiently because the end 6 will bind upon the inner face of the transverse opening 4. It will be seen that when this end 6 is in the described position, 75 that it will efficiently prevent the accidental displacement of the key so that the same will not be easily knocked out but will not prevent the same being driven out if so desired.

The main purpose of the slots 8 and 9 is to allow the key to be easily inserted within the transverse opening 4. By referring to Figs. 1 and 2, it will be seen that the slots are adapted to extend parallel with 85 the face 11 of the nut so that when the key is driven into the aperture the threaded portion 2 will go between the bifurcated portions, thereby making it easy for the threads to cut into the key as is shown in 90 Fig. 3. By having the threads cut into the key, it will be seen that the key may be removed from the opening 4 without injuring the threads so that the bolt may be used indefinitely.

95 From the above description, it will be seen that a nut lock has been produced which is provided with a key which will tangentially engage the threaded portion of the nut in such a manner as to efficiently prevent the 100 rotation of a nut and at the same time the key may be inserted or removed without substantially injuring the threaded portion of the bolt. It will also be seen that a key has been provided with a construction which 105 will allow the key to be sufficiently locked within the nut so as to prevent the accidental displacement of the said key.

What I claim is:

1. In a device of the class described, the 110 combination of a bolt, a nut carried upon said bolt, a transverse opening provided

wholly within the body of said nut, a key adapted to be inserted within said nut, said key provided with slots at each of its ends, said slots adapted to extend parallel with the under face of said nut so as to allow said key to be inserted within said slot in such a manner that the threads will easily cut into said key.

2. In a device of the class described, the combination of a bolt, a nut carried upon said bolt, a transverse opening provided wholly within the body of said nut, a key adapted to be inserted within said nut, said key provided with slots at each of its ends,

said slots adapted to extend parallel with the under face of said nut, one end of said key being beveled so as to fit flush with the corresponding side of said nut, said end provided with a channel extending within said slot whereby a pointed instrument may be driven in said channel so as to spread said slot, thereby efficiently locking said key within said nut so as to prevent the accidental displacement of the same.

In testimony whereof I hereunto affix my signature.

JOHN J. MACKAY.
